UNITED STATES PATENT OFFICE.

ALBERT D. WILKINSON, OF METHUEN, MASSACHUSETTS.

HEADLIGHT.

Application filed October 24, 1921. Serial No. 509,997.

To all whom it may concern:

Be it known that I, ALBERT D. WILKINSON, a citizen of the United States, residing at Methuen, in the county of Essex and State of Massachusetts, have invented new and useful Improvements in Headlights, of which the following is a specification.

This invention relates to headlights for motor vehicles, a headlight to which the invention relates including a paraboloidal reflector and an incandescent electric lamp, or other source of light, located in front of the focal point of the reflector, the direct and reflected rays from the source of light being projected forward through the open end or mouth of the reflector.

The object of the invention is to provide simple and effective reflecting means, adapted to project reflected rays in such directions as to suitably illuminate the track ahead of the vehicle, without projecting glaring rays into the eyes of persons toward whom the vehicle is moving, said means including a paraboloidal main reflector, and segmental reflectors of simple construction cooperative therewith to produce the desired result.

The invention is embodied in the improvements hereinafter described and claimed.

Of the accompanying drawings forming a part of this specification,—

Figure 1 shows in vertical section a paraboloidal reflector and segmental reflectors associated therewith in accordance with the invention, and in side elevation a source of light.

Figure 2 is a horizontal section on line 2—2 of Figure 1, and a plan view of the segmental reflectors.

Figure 3 shows the segmental reflectors in perspective, detached from the paraboloidal reflector.

The same reference characters indicate the same parts in all of the figures.

In the drawings, 12 represents a paraboloidal reflector hereinafter called the main reflector, and 13 represents a source of light, such as an incandescent electric lamp in front of the focal point of the main reflector.

Light rays reflected from the upper half, when the axis of the reflector is horizontal, are projected forward and downward, but not upward, as indicated by the angular dotted lines 14 in Figure 1.

15 represents a lower segmental reflector, which is a segment or half section of a sub-

stantially frusto-conical tube, deviating from a true frusto-conical form in that it is curved and presents an inner surface which is longitudinally convex. The segmental reflector 15 is arranged with its convex surface facing upward, said surface being suitably finished as a reflecting surface. The larger end of the reflector 15 is seated on the lower half of the mouth of the main reflector, and its smaller end is spaced from the main reflector, as shown by Figure 1.

16 represents an upper segmental reflector, which is a segment or half section of a substantially conical hollow body, deviating from a true conical form in that it presents an outer surface which is longitudinally convex, and an inner surface which is longitudinally concave. The segmental reflector 16 is arranged with its convex surface facing downward, said surface being suitably finished as a reflecting surface. The reflectors 15 and 16 are coaxial with the main reflector 12, and occupy the lower half of the latter. The lower reflector 15 is suitably secured to, and supported by, the main reflector, and the upper reflector 16 is supported by the lower reflector, preferably through the instrumentality of a curved standard 18, fixed at its ends to said reflectors.

To secure the lower reflector to the main reflector, I preferably provide the outer end of the lower reflector with a segmental flange 19, which is formed to be seated on the lower half of a continuous flange 20, surrounding the mouth of the main reflector, and connected with the last-named flange by a hinge which permits the segmental reflectors to be swung outward from the main reflector, to afford access to the lamp 13. Said hinge may include a tubular member 21, on the flange 19, tubular members 22, 22 on the flange 20, and a pintle member 23 connecting said tubular members.

The form of the segmental reflectors and their arrangement relatively to each other, to the source of light, and to the main reflector, are such that the following results occur: Light rays reflected from the inner portion of the lower half of the main reflector are projected between the segmental reflectors and reflected forward and downward, but not upward, as indicated by the angular dotted lines 25, some of said rays being reflected by the upper reflector, others by the lower reflector, and others by both reflectors. Some of the direct rays are pro-

jected between the upper and lower reflectors, as indicated by the straight dotted lines 26. Light rays reflected by the outer portion of the lower half of the main reflector are intercepted by the lower reflector 15 and are not projected. These rays, as will now be seen, are projected forward and downward, but not upward:

The upper side of the upper reflector 16 10 forms a channel through which reflected rays, indicated by the lower line 14, are projected, as shown by Figure 1.

The reflectors above described may be installed in a suitable case, having a hinged 15 door which includes a glass panel or lens, the door, when closed, confining the several reflectors.

The reflectors are adapted to project light rays obliquely forward and downward and 20 illuminate a wider area of the track than would be possible without the segmental reflectors 15 and 16.

I claim:

1. In a headlight, in combination, a main 25 paraboloidal reflector; a source of light; a substantially segmental lower reflector; means displaceably securing the lower reflector to the main reflector; a substantially segmental upper reflector, and means connecting said segmental reflectors, so that the upper reflector is supported by, and spaced from the lower reflector, and is displaceable

with the latter, said segmental reflectors being located within the lower half of the main reflector, and permitting the light rays reflected from said lower half to be projected between the segmental reflectors forward and downward, but not upward, the segmental reflectors being out of the path of light rays reflected from the upper half of the 40 main reflector.

2. In a headlight, in combination, a main paraboloidal reflector provided with a flange at its outer end, a substantially segmental lower reflector provided at its outer end with a segmental flange seated on the main reflector flange and hinged thereto, to swing toward and from the main reflector flange; a substantially segmental upper reflector, and a standard whereby the upper reflector is 50 connected with, and spaced from the lower reflector, for movement in unison with the latter, said segmental reflectors being located within the lower half of the main reflector, and out of the path of rays reflected 55 from the upper half of the latter, and permitting the light rays reflected from said lower half to be projected between the segmental reflectors forward and downward, but not upward.

In testimony whereof I have affixed my signature.

ALBERT D. WILKINSON.
